United States Patent Office

Des. 229,529

Patented Dec. 11, 1973

229,529

DESK

Frank Gallagher, Manhasset, and Gordon Perry, Bayside, N.Y., assignors to Oxford Pendaflex Corporation, Garden City, N.Y.

Filed Apr. 17, 1972, Ser. No. 245,015

Term of patent 14 years

Int. Cl. D6—03

U.S. Cl. D6—177

FIG. 1

FIG. 2

FIG. 3

FIG. 4

FIG. 5

FIG. 1 is a rear perspective view of a desk embodying our new design wherein support means for a portion of said desk are illustrated in dotted lines;

FIG. 2 is a front perspective view thereof;

FIG. 3 is a plan view thereof;

FIG. 4 is a front view thereof; and

FIG. 5 is a rear view thereof.

We claim:

The ornamental design for a desk, as shown.
